UNITED STATES PATENT OFFICE.

DUANE P. FULLER, OF CARLISLE, WASHINGTON.

OPERATING MECHANISM FOR WHISTLES.

1,328,252.

Specification of Letters Patent. Patented Jan. 13, 1920.

Application filed April 9, 1919. Serial No. 288,697.

To all whom it may concern:

Be it known that I, DUANE P. FULLER, a citizen of the United States, residing at Carlisle, in the county of Grays Harbor and 5 State of Washington, have invented certain new and useful Improvements in Operating Mechanism for Whistles, of which the following is a specification.

This invention relates to an improvement 10 in an operating mechanism for whistles, whereby the whistle may be operated from a remote point with a certainty of control and operation substantially equal to that of a short whistle cord.

15 It is particularly desirable in some operations, as in logging, that means be provided to permit the remote workman to signal to the engineer of the stationary engine employed as to what action is desired. This is 20 usually done by providing an ordinary type of whistle, or other manually operable alarm, on or adjacent the engine, with the operating means thereof extending a considerable distance. It has heretofore been 25 proposed to connect a whistle cord to a spring post, and also to connect the operating cord to said post. The pull on the operating cord is designed to move the upper end of the post to thereby actuate the whistle cord and 30 thereby sound a whistle. This can be readily accomplished by the operating cord extending in line with the whistle cord, but even then the vibration of the post will materially interfere with, if not preclude, a 35 series of whistle signals in rapid succession, as may be necessary. Furthermore unless the operating cord extends in a direct line with the whistle cord, as for example if it should extend at right angles thereto, the 40 device described would be practically inoperative.

The present invention overcomes these objections by providing means to eliminate the vibration of the post, and to permit the operating cord to extend in any direction, from, and with the respect to, the whistle 45 cord.

In the drawings:—

Figure 1 is a side elevation illustrating the 50 invention.

Fig. 2 is a side elevation of the upper end of the movable post.

Fig. 3 is a plan of the same.

Fig. 4 is a side elevation, and Fig. 5 a 55 front elevation of the operating cord guiding means.

For convenience and illustration the improved alarm is here shown as a whistle 2, mounted upon an ordinary type of donkey or other engine 1, such illustration of course 60 indicating any type of manually operable signal and any power plant.

Whistle 2 is of any usual or preferred type, here shown as a steam whistle, normally held closed in any appropriate manner and opened for alarm sounding purposes in the operation of lever 3.

A post 10 is pivotally mounted at 11, on the engine base, or other support adjacent the engine. The upper end of the post 10 70 is provided with a casting having a pair of horizontally disposed spaced parallel guide rollers 5 rotatively mounted in such casting.

A second post 13 is rigidly mounted on the engine, base or other support, and is provided at the upper end with a bracket carrying vertically arranged spaced parallel guide rollers 9.

The whistle cord 4 is connected at one end to the whistle lever 3, passes over one of the 80 rollers 5 from above, and downwardly to a point in advance of the post 10, and terminally fixed at 6. The operating cord 8 is terminally wound about a drum as 7, mounted upon a support between the posts 10 and 85 13. The drum is provided with an operating handle whereby the cord 8 may be wound thereon when not required for use and may have an ordinary dog and ratchet to prevent unwinding of the drum after a 90 sufficient length of cord 8 has been unwound from the drum to extend such cord to the point required. The cord 8 extends from the drum forwardly and over the remaining roller 5 from beneath, being then passed 95 between the rollers 9, and led therefrom in any desired direction.

A pull on the cord 8, no matter in what direction it may extend from the post 13, will move the upper end of the post 10 from 100 the whistle, pulling upon lever 3 through the whistle cord 4 and sounding the whistle. Upon release of the pull on cord 8 the spring of the whistle returns the post 10 to normal position, through the whistle cord, the depending portion of such cord preventing any vibratory movement of such post. The whistle may be thus sounded in quick succession by proper operation of the cord 8, substantially the same as if the whistle cord 110 was being directly operated.

What is claimed, is:—

1. Means for transmitting motion comprising a pivoted post, a cord fastened at one end and having a sliding coöperation with the post, the other end of the cord extending away from said post, and an operating cord having a fixed terminal and an operating terminal, said operating cord having sliding connection with the post between its terminals.
- 10 2. Means for transmitting motion comprising a pivoted post, a cord having a slid-

ing coöperation with the post, one terminal of the cord being fixed and the other terminal extending from the post and an operating cord having a fixed terminal and an 15 operating terminal, said operating cord having sliding connection with the post between its terminals, and a drum about which the operating cord may be wound to serve as the fixed terminal of such cord.

20 In testimony whereof I affix my signature.
DUANE P. FULLER.
